Primary Examiner — Jasmine Mlinarcik(74) Attorney, Agent, or Firm — JoAnn M. Seaton; Griffiths & Seaton PLLC(57) CLAIM

The ornamental design for an activewear legging, as shown and described.

DESCRIPTION

FIG. 1 is a top, front perspective view of an activewear legging showing our new design;

FIG. 2 is a top, rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

In the drawings, inside portions of the activewear legging are unclaimed and therefore are unshaded.

1 Claim, 6 Drawing Sheets(56)
